UNITED STATES PATENT OFFICE

JOHN A. HERSHY, OF CHERRYVILLE, PENNSYLVANIA

SCAFFOLDING

Application filed October 1, 1931. Serial No. 566,345.

My invention relates to the art of scaffolding such as is frequently used by carpenters, house painters, brick masons, wall cleaners, tinniers, plasterers, etc., and it particularly has for an object to provide a scaffold that can be easily carried in collapsed condition on a truck from place to place and unloaded and set up for use in a few moments.

Further, the invention has for an object to provide an extensible ladder having telescopic posts on which is mounted a vertically adjustable platform.

Further, the invention has for an object to provide mechanism whereby the platform may be moved up or down to any desired height and held there.

Further, it is an object to provide means operable from the platform for extending and retracting the telescopic sections of the ladder's posts by the raising and lowering respectively of the platform when connected to the sections of the posts to be moved.

Further, it is an object to provide a ladder whose posts or standards are supported on wheels and are held in upright position by suitable braces and guide wheels, all in a manner so that the ladder may be moved from place to place while in its assembled and operative condition.

Further, it is an object to provide a scaffold-ladder of all metal construction which nevertheless may be comparatively light in weight while possessing maximum strength of parts.

Further, it is an object of the invention to provide a platform moving and post adjusting mechanism which includes a double over-reach pawl jack and a safety latch, the latter serving to hold the platform and sections of posts from dropping while being extended.

Other objects will in part be obvious and in part be pointed out hereinafter.

To the attainment of the aforesaid objects and ends, the invention still further resides in the novel details of construction, combination and arrangement of parts, all of which will be first fully described in the following detailed description, then be particularly pointed out in the appended claims, reference

being had to the accompanying drawings, in which:

Figure 1 is a front elevation of my invention.

Figure 2 is a side elevation of the same. 55

Figure 3 is a plan view thereof.

Figure 4 is an enlarged detail elevation and part section showing the extending and retracting mechanism of the posts and the platform adjusting mechanism in position for 60 raising the platform and extending the sections of the posts.

Figure 5 is a view similar to Figure 4 showing the position of the parts when the platform is to be lowered. 65

Figure 6 is a detail section on the line 6—6 of Figure 4.

Figure 7 is a horizontal section on the line 7—7 of Figure 4.

Figure 8 is an enlarged detail view showing how the hinged base sub-frame may be folded up and secured to the post. 70

Figure 9 is a horizontal section on the line 9—9 of Figure 8.

Figure 10 is a detail perspective view showing one of the brackets for holding the posts from the wall. 75

Figure 11 is a detail perspective view showing how the temporary legs hold the posts in position while assembling the parts. 80

In the drawings, in which like numerals of reference designate like parts in all of the figures, 1 represents the lower or base section of the telescopic post, 2 the intermediate section and 3 the upper section thereof. Collars 85 4 are provided at the upper ends of the post sections and carry set screws 5, or clamp screws, to hold the sections against moving with respect to one another after having once been adjusted.

In order that the ladder may be moved along the building wall with little effort, I prefer to mount the posts on wheels 6 and provide a handle 7 by which the ladder may 95 be pulled or pushed from place to place. 8 designates laterally extended feet which are hinged at 9 to the post sections 1 and are provided with crossed braces 10, the outer ends of the feet 8 carrying small wheels 11 100

serving as auxiliary supporting wheels to the wheels 6.

5 Side braces 12 composed of extensible bars connect at 16 with the feet 8 and post sections 1 respectively as best shown in Figure 2 of the drawings, they being provided with one or more clamps 13 to secure the extensible sections of the braces rigidly together in a proper position to maintain the posts in 10 a vertical position.

14 is a diagonal brace bar connecting the lower end of one post with the upper end of the other post as at 16a, the bar 14 being preferably composed of extensible bars secured 15 by one or more clamps 15 into a rigid member.

17 designates spacer brackets, one for each post, these brackets extending at right angles to the posts toward the building and 20 serving to space the posts a definite distance from the building. These brackets 17 each have a bifurcated end providing a lower finger 18 having a shoulder 19 and an upper finger 20 having a double T head 21, the purpose of which will presently appear.

30 One face of the posts, preferably the outer face, i. e. the face located away from the building, is provided with a vertical series of perforations 22 while the opposite face is provided with a continuous slot 23.

35 The carriage on which the platform and the jack mechanism is mounted comprises a casting 24 into which is fitted a guard rail 25. The casting 24 also carries wheels 26 which run within the hollow posts, the casting projecting through the vertical slot 23 as best shown in Figure 7 of the drawings. The casting 24 has a vertical extension 27 on which is pivoted at 32 a pair of gripper levers 28 which are normally held spread apart to engage the inner side walls of the post sections, through the medium of a suitable spring 29. The grippers have recesses 30 to receive lugs 31 located adjacent the lower extremities of the intermediate and upper telescoping sections of the posts.

50 33 is a gripper spreader crank shaft whose head 34 is located between the arms of the gripper to which the spring 29 is fastened. When the head 34 is in one position the spring functions to hold the gripper with its recesses 30 over the lugs 31, but when the crank shaft 33 is turned to turn the head 34 the 55 arms having the spring attached will be spread apart and consequently the recesses 30 and lugs 31 will be disengaged to leave the grippers free from the post sections. In order to hold the spreader head in the gripper releasing position the gripper arms may have V-shaped notches 35 in which the corners of the spreader head may rest.

60 36 designates upright bars or plates secured at 37 to the casting 24 and extending downwardly paralleling the posts, the bars 65

being also secured at 42 to the platform supporting horizontal bar 38.

65 The horizontal bar 38 is provided with a leg 39 suitably braced at 40 and carrying a set of wheels 41 to work in the hollow post, the wheels 41 and 26 serving to retain the carriage on the post and guide it in its travel lengthwise of the post. In order to hold the carriage in any of its adjusted positions up and down the post I provide a back check or 70 safety pawl 43 which may be released, however, by manipulating a releasing lever 44 which is connected to the pawl by a suitable connecting rod 45 so that when the user, standing on the platform 46, desires to release the pawl 43 all he need do is to put his foot on the release lever 44 and press it down. 75

80 The main jack lever 47 is fulcrumed at 48 between the bars 36 and a suitable distance above the platform 46. The lever 47 carries two pawls, the lower one 49 of which is fulcrumed at 51 on the inner end of the lever 47 and is held to engage in the apertures 22 of the post under normal conditions by means of a suitable pressing spring 50. 85

90 The pawl 49 may, however, be released from its engagement with the post and held in the released position by means of a releasing mechanism which consists of a pawl-release-control slide 52 slidably mounted on the lever 47 and projecting to either side of its fulcrum. The slide 52 carries the throw-out spring 53 which engages the heel of the pawl 49 when the slide is moved toward the pawl a distance sufficient to cause the force 100 of the spring 53 to overcome that of the spring 50. This movement of the slide is accomplished by means of a slide actuating bell crank 54 fulcrumed at 55 on the outer portion of the lower jack lever 47 and having 105 a pin and slot connection 56 with the slide. When the lever 54 is pressed downwardly and held locked to the lever 47 by the latching lug 64 engaging under the lever 47, the slide 52 will be held in its forward position, 110 thus placing the spring 53 under sufficient tension to overcome that of the spring 50.

115 The upper pawl 57 is fulcrumed at 55 to the lever 47 and projects over the slide 52 and pawl 49 to engage in an aperture 22 above that engaged by the pawl 49. The upper pawl 57 is held in its engaged position by a pressing spring 58.

120 A release dog 59 is pivoted between the bars 36 beneath the pawl 57 to engage its underside at times, the release dog being pivoted at 60 and provided with a pressing spring 61 which does not function at all times but only when its free end 62 is engaged by the projection 63 on the slide 52 125 when that projection is moved forwardly during the rocking of the lever 47.

130 The upper extremities of the pair of posts are cross braced by a horizontal bar 65 detachably secured to the upper ends of the

upper post sections by means of suitable winged screws 162 or their equivalents.

5 66 designates foot cups in which the wheels 6 may be set to prevent movement of the ladder when desired. These cups may be of any suitable construction for the purpose.

10 67 designates auxiliary feet, the purpose of which is to assist in the assembling of the ladder. These feet are pivoted at 68 to the lower sections of the posts and include an angle plate 69 and a pair of scissors-like portions 70 which are pivoted to the angle plate as at 71 and have stops 72 to engage the sides of the angle plate 69 when the members 70 are spread apart. When the members 70 are spread apart and swung out from the base section 1 of the post, they may be engaged with the ground to hold the post inclined to a suitable angle to the horizontal, leaving 20 the side of the ladder which is to face the house uppermost so that the carriage and jack mechanism may be placed in position with ease.

25 When not in use the auxiliary feet are held folded against the post by a suitable clamp device 73 which also serves to hold the laterally extending feet 8 folded up against the post when the parts are collapsed for shipment.

30 Of course, the sections of the posts may be placed in their more or less extended position by hand without the use of the jack mechanism during the assembling of the structure, but where adjustments are to be made after 35 the ladder is in position for use the jack mechanism is especially useful.

40 The spacer brackets 17 may be located at any height desired since it is only necessary to raise up on the free ends of these brackets to bring the fingers 18 out of the holes 22 when the brackets may be raised and lowered and those fingers brought into engagement with other holes.

45 It will be seen that the brackets 17 cooperate with the laterally extended feet 8, etc., to maintain the posts of the ladder vertical and at all times parallel to the building being worked on, and in consequence thereof the platform is maintained at a horizontal position.

50 When it is desired to raise and lower the platform without effecting the extensibility of the post sections, the operator turns the crank shaft 33 to release the grippers and hold them released. Then by working the lever 47 up and down with the lever 54 released the platform may be raised to the position desired. When the lever 54 is elevated, as shown in Figure 4, the spring 50 is enabled to exert its force on the pawl 49 continuously tending to hold that pawl in contact with the member 1 so that it will enter the openings 22 in climbing up the member 1. Also, the pawl 57 will continuously tend 65 to engage the member 1 to enter the openings

22. Hence as 47 is rocked up pawl 49 will hang in an opening 22 while pawl 57 withdraws from the opening in which it is shown and enters the next opening above. Then, on the downward stroke of the lever 47, pawl 70

57 will hang in its opening and pawl 49 will rise to the opening in which pawl 57 was previously hooked. Pawl 43 acts as a safety or back-check pawl during this raising movement. To lower the platform the lever 54

75 is pressed down and latched to the lever 47 and then by putting the foot on the lever 44 and releasing the check pawl 43 and rocking the lever 47, the platform may be lowered step by step. When the lever 54 is depressed

80 and held there, as shown in Figure 5, it will cause the slide 52 to push the spring 53 against the short end of the pawl 49 to overcome the force of the spring 50 and hold the pawl 49 at a fixed angle to the lever 47, as

85 shown in Figure 5. Also, the member 63 pressing against the spring 62, puts it under tension and causes pawl 59 to tend to release pawl 57. Now, as soon as the lever 47 is

90 started upwardly the pawl 49 will engage the notch 22 in Figure 5, just below the one where the pawl head is opposite, and the weight of the platform will then be carried by the pawl 49. Carrying the weight of the platform

95 by the pawl 49, the weight is relieved from pawl 57 which is withdrawn from the notch by the spring pawl 59. The lever 47 is then lowered with the pawl 49 hooked in the lower notch 22 until the pawl 57 engages the notch

100 22 just below the one with which it is shown in engagement in Figure 5. When this occurs the weight of the platform will be taken by the pawl 57 and the spring 53 will ensure the release of the pawl 49. This operation is

105 repeated, thus lowering the platform one notch at a time. As soon as the platform shall have been lowered to the desired position the lever 44 is released and pawl 43 comes into action again as a safety device. When

110 it is desired to use the jack mechanism for extending and contracting the sections of the post the operator turns the crank shaft 33 to release the grippers and enable it to engage the lugs 31 on the post sections. Thus,

115 as the platform is raised and lowered in the manner hereinbefore described, the connected telescopic post sections will be correspondingly raised and lowered, it being, of course, understood that before the raising and lowering movement takes place the clamp mem-

120 bers 5 are loosened.

125 From the foregoing description, taken in connection with the accompanying drawings, it is thought the construction, operation and advantages of the invention will be clear to those skilled in the art. I might say in conclusion that it will be evident from the foregoing that the scaffold is especially adapted

130 for any surface painting jobs and stuccoing work, etc. due to its convenience and the

comfort afforded the users, also due to the time and labor saved since the scaffold can be unloaded from a truck and assembled ready for work with but two points touching the building. The platform can be raised from the ground to the top for bricklayers, for cleaning bricks and walls, laying up outside of chimneys, house wall repairs as repairs to weather boarding, etc., all without moving the ladder for the purpose of raising and lowering the platform. It is also especially adapted for tinnings' use in placing cornice work and starting in the roof at its lower edge. Since the scaffold is not fastened to the building it is especially useful in stucco work. Since it is located at the same distance from the building from top to bottom it can be used with great facility by tinnings for placing downspouts, gutters and gutter hooks.

While I have disclosed the preferred embodiment of my invention it is obvious that changes in the details of construction, design and form of parts may readily be made without departing from the spirit of the invention or the scope of the claims.

What I claim is:

1. In scaffolding, a scaffolding comprising tubular telescoping-section posts, means to support said posts in vertical position, a platform, carriages for said platform which are vertically movably mounted on said posts, and mechanism on said carriages for raising and lowering said platform and extending and retracting said post sections, said posts having means cooperating with said mechanism for the purpose stated.

2. In scaffolding, a scaffolding comprising tubular telescoping-section posts, means to support said posts in vertical position, a platform, carriages for said platform which are vertically movably mounted on said posts, the sections of said posts having a vertical series of apertures in one face and a vertical slot in the face opposite thereto, said carriages having portions extending through said slots into said posts, and platform lifting and lowering jack mechanism including an operating lever and pawl elements cooperating with said vertical series of apertures.

3. In scaffolding, a scaffolding comprising tubular telescoping-section posts, means to support said posts in vertical position, a platform, carriages for said platform which are vertically movably mounted on said posts, the sections of said posts having a vertical series of apertures in one face and a vertical slot in the face opposite thereto, said carriages having portions extending through said slots into said posts, platform lifting and lowering jack mechanism including an operating lever and pawl elements cooperating with said vertical series of apertures, check pawls carried by said carriages to en-

gage in said apertures, and pawl releasing means for said check pawls.

4. In scaffolding and the like, a hollow post comprising a base section and a top and intermediate sections telescoping into one another, a laterally extended foot located at the bottom of said base section, a brace for holding said foot to support said post in vertical position, a carriage vertically movably held on said post, means to raise and lower said carriage, and means on said carriage to engage the telescoping sections of said post to project and retract the same accordingly as said carriage is raised or lowered.

5. In scaffolding and the like, a hollow post comprising a base section and a top and intermediate sections telescoping into one another, a laterally extended foot located at the bottom of said base section, a brace for holding said foot to support said post in vertical position, a carriage vertically movably held on said post, means to raise and lower said carriage, means on said carriage to engage the telescoping sections of said post to project and retract the same accordingly as said carriage is raised or lowered, said means comprising a post section gripper on the carriage and lugs on the post sections to be engaged by said gripper.

6. In scaffolding and the like, a hollow post comprising a base section and a top and intermediate sections telescoping into one another, a laterally extended foot located at the bottom of said base section, a brace for holding said foot to support said post in vertical position, a carriage vertically movably held on said post, means to raise and lower said carriage, means on said carriage to engage the telescoping sections of said post to project and retract the same accordingly as said carriage is raised or lowered, said means comprising a post section gripper on the carriage and lugs on the post sections to be engaged by said gripper, and manually controlled means to render said gripper operative or inoperative at will.

7. In scaffolding and the like, a hollow post comprising a base section and a top and intermediate sections telescoping into one another, said telescoping sections having a wall provided with apertures, a laterally extended foot located at the bottom of said base section, a brace for holding said foot to support said post in vertical position, a carriage vertically movably held on said post, mechanism to raise and lower said carriage, means on said carriage to engage the telescoping sections of said post to project and retract the same accordingly as said carriage is raised or lowered, said mechanism comprising a main jack lever, a pair of over-reaching pawls carried thereby to engage said apertures in a wall of the telescoping post sections, and means to reverse the action of said pawls at will.

8. In scaffolding and the like, a hollow post comprising a base section and a top and intermediate sections telescoping into one another, said telescoping sections having a wall provided with apertures, a laterally extended foot located at the bottom of said base section, a brace for holding said foot to support said post in vertical position, a carriage vertically movably held on said post, mechanism to raise and lower said carriage, means on said carriage to engage the telescoping sections of said post to project and retract the same accordingly as said carriage is raised or lowered, said means comprising a post section gripper on the carriage and lugs on the post sections to be engaged by said gripper, said mechanism comprising a main jack lever, a pair of over-reaching pawls carried thereby to engage said apertures in a wall of the telescoping post sections, and means to reverse the action of said pawls at will. 70
9. In scaffolding and the like, a hollow post comprising a base section and a top and intermediate sections telescoping into one another, said telescoping sections having a wall provided with apertures, a laterally extended foot located at the bottom of said base section, a brace for holding said foot to support said post in vertical position, a carriage vertically movably held on said post, means to raise and lower said carriage, means on said carriage to engage the telescoping sections of said post to project and retract the same accordingly as said carriage is raised or lowered, a back check pawl pivoted to said carriage to engage in the apertures of said post sections, and check-pawl-controlling means on said carriage. 80
10. In scaffolding and the like, a hollow post comprising a base section and a top and intermediate sections telescoping into one another, said telescoping sections having a wall provided with apertures, a laterally extended foot located at the bottom of said base section, a brace for holding said foot to support said post in vertical position, a carriage vertically movably held on said post, mechanism to raise and lower said carriage, means on said carriage to engage the telescoping sections of said post to project and retract the same accordingly as said carriage is raised or lowered, said means comprising a post section gripper on the carriage and lugs on the post sections to be engaged by said gripper, manually controlled means to render said gripper operative or inoperative at will, said mechanism comprising a main jack lever, a pair of over-reaching pawls carried thereby to engage said apertures in a wall of the telescoping post sections, and means to reverse the action of said pawls at will. 90
11. In scaffolding and the like, a hollow post comprising a base section and a top and intermediate sections telescoping into one another, said telescoping sections having a wall provided with apertures, a laterally extended foot located at the bottom of said base section, a brace for holding said foot to support said post in vertical position, a carriage vertically movably held on said post, mechanism to raise and lower said carriage, means on said carriage to engage the telescoping sections of said post to project and retract the same accordingly as said carriage is raised or lowered, said mechanism comprising a main jack lever, a lower pawl pivoted to the inner end thereof and engaging said apertures in a wall of said telescoping post sections, a spring to press said lower pawl into engaging position, an upper pawl pivoted to said lever on the outer side of its fulcrum, a spring to press said upper pawl into engagement with the apertures in the wall of the telescoping post sections, an upper pawl throw-out dog on said carriage, a pawl-controlling slide on said main operating lever having provisions to cooperate with said lower pawl and said dog, a slide shifting auxiliary lever fulcrumed on said main operating lever and cooperatively connected to said slide, a back check pawl pivoted to said carriage to engage in the apertures of said post sections, and check-pawl-controlling means on said carriage. 100
12. In scaffolding and the like, a hollow post comprising a base section and a top and intermediate sections telescoping into one another, said telescoping sections having a wall provided with apertures, a laterally extended foot located at the bottom of said base section, a brace for holding said foot to support said post in vertical position, a carriage vertically movably held on said post, mechanism to raise and lower said carriage, means on said carriage to engage the telescoping sections of said post to project and retract the same accordingly as said carriage is raised or lowered, said mechanism comprising a main jack lever, a lower pawl pivoted to the inner end thereof and engaging said apertures in a wall of said telescoping post sections, a spring to press said lower pawl into engaging position, an upper pawl pivoted to said lever on the outer side of its fulcrum, a spring to press said upper pawl into engagement with the apertures in the wall of the telescoping post sections, an upper pawl throw-out dog on said carriage, a pawl-controlling slide on said main operating lever having provisions to cooperate with said lower pawl and said dog, a slide shifting auxiliary lever fulcrumed on said main operating lever and cooperatively connected to said slide, a back check pawl pivoted to said carriage to engage in the apertures of said post sections, and check-pawl-controlling means on said carriage. 110
13. In apparatus of the kind described, a post comprising a plurality of nesting-telescoping-hollow post sections, the inner sections having internal lugs adjacent their lower ends, a carriage having upper and 120
14. In scaffolding and the like, a hollow post comprising a base section and a top and intermediate sections telescoping into one another, said telescoping sections having a wall provided with apertures, a laterally extended foot located at the bottom of said base section, a brace for holding said foot to support said post in vertical position, a carriage vertically movably held on said post, mechanism to raise and lower said carriage, means on said carriage to engage the telescoping sections of said post to project and retract the same accordingly as said carriage is raised or lowered, said mechanism comprising a main jack lever, a lower pawl pivoted to the inner end thereof and engaging said apertures in a wall of said telescoping post sections, a spring to press said lower pawl into engaging position, an upper pawl pivoted to said lever on the outer side of its fulcrum, a spring to press said upper pawl into engagement with the apertures in the wall of the telescoping post sections, an upper pawl throw-out dog on said carriage, a pawl-controlling slide on said main operating lever having provisions to cooperate with said lower pawl and said dog, a slide shifting auxiliary lever fulcrumed on said main operating lever and cooperatively connected to said slide, a back check pawl pivoted to said carriage to engage in the apertures of said post sections, and check-pawl-controlling means on said carriage. 130

lower wheel sets located in said hollow post, said post having a longitudinal slot through which said carriage projects, a jack mechanism on said carriage for moving it along said slot, and releasable means on said carriage to engage said post lugs for extending and retracting said nesting-post sections accordingly as said carriage is jacked in one direction or another.

14. In apparatus of the kind described, a post comprising a plurality of nesting-telescoping-hollow post sections, the inner sections having internal lugs adjacent their lower ends, a carriage having upper and lower wheel sets located in said hollow post, said post having a longitudinal slot through which said carriage projects, a jack mechanism on said carriage for moving it along said slot, releasable means on said carriage to engage said post lugs for extending and retracting said nesting-post sections accordingly as said carriage is jacked in one direction or another, and means to secure the post sections together rigidly after they have been extended.

15. In apparatus of the kind described, a post comprising a plurality of nesting-telescoping-hollow post sections, the inner sections having internal lugs adjacent their lower ends, a carriage having upper and lower wheel sets located in said hollow post, said post having a longitudinal slot through which said carriage projects, a jack mechanism on said carriage for moving it along said post, releasable means on said carriage to engage said post lugs for extending and retracting said nesting-post sections accordingly as said carriage is jacked in one direction or another, and means to hold said post in vertical position, said means including a building engaging bracket adjustably held in said post and projecting through the slot thereof to space the post from the building.

16. In apparatus of the kind described, a post comprising a plurality of nesting-telescoping-hollow post sections, the inner sections having internal lugs adjacent their lower ends, a carriage having upper and lower wheel sets located in said hollow post, said post having a longitudinal slot through which said carriage projects, a jack mechanism on said carriage for moving it along said slot, releasable means on said carriage to engage said post lugs for extending and retracting said nesting-post sections accordingly as said carriage is jacked in one direction or another, means to secure the post sections together rigidly after they have been extended, and means to hold said post in vertical position, said means including a building engaging bracket adjustably held in said post and projecting through the slot thereof to space the post from the building.

17. In apparatus of the class described, a tubular telescopic sectional post with means

to hold the sections rigidly together in extended relation, said sections each having a wall with a vertical series of apertures and having a vertically slotted wall, and a spacer bracket extended through the slot and having an upper finger and a lower finger, the upper finger having a head to engage the inner side of the slotted wall and the lower finger having a shouldered tip to engage the apertured wall of the post.

18. In apparatus of the class described, a tubular telescopic sectional post with means to hold the sections rigidly together in extended relation, said sections each having a wall with a vertical series of apertures and having a vertically slotted wall, and a spacer bracket extended through the slot and having an upper finger and a lower finger, the upper finger having a head to engage the inner side of the slotted wall and the lower finger having a shouldered tip to engage the apertured wall of the post, and a foot extending from the bottom of the post in a direction opposite to that of said spacer bracket for the purposes described.
